Attorneys.

UNITED STATES PATENT OFFICE.

GEORGE H. BARSCHOW, OF TOLEDO, OHIO.

HIGH CHAIR.

1,187,483.

Specification of Letters Patent. Patented June 20, 1916.

Application filed July 2, 1914. Serial No. 848,649.

To all whom it may concern:

Be it known that I, GEORGE H. BARSCHOW, a citizen of the United States, and a resident of Toledo, in the county of Lucas and State 5 of Ohio, have invented a certain new and useful High Chair; and I do hereby declare the following to be a full, clear, and exact description of the invention, such as will enable others skilled in the art to which it applies 10 to make and use the same, reference being had to the accompanying drawings, and to the characters of reference marked thereon, which form a part of this specification.

This invention relates to folding chairs, and particularly to a high-chair, but is not restricted to such use as it may be used in any connection for which it may be adapted or appropriate.

20 The primary object of my invention is the provision of a high-chair of the character described, which is easy and inexpensive to manufacture, light, strong and durable in its construction and capable of being folded 25 or collapsed into compact form to facilitate a packing or storing thereof.

Further objects and advantages of the invention will be apparent from the following detailed description thereof.

30 The invention is fully described in the following specification, and while, in its broader aspect, it is capable of embodiment in numerous forms, a preferred embodiment thereof is illustrated in the accompanying 35 drawings, in which,—

Figure 1 is a perspective view of a chair embodying the invention in set-up form. Fig. 2 is a side view of the chair partly collapsed, and Fig. 3 is a similar view of the 40 chair completely collapsed.

Referring to the drawings, 1 and 2 designate 45 forwardly extending base members or bars which coöperate with front and rear cross-bars 3 and 4, respectively, to form a base frame of rectangular form. Pivotally rising from the base members or bars 1 and 2, adjacent to the front and rear ends thereof, are upright bars 5 and 6, respectively, which, in the present instance, 50 are of the same length and have their lower ends formed with outwardly projecting feet 7 for resting on a floor or other subjacent support when the chair is in set-up position. The front corner bars 5, 5 are carried, in

the present instance, at the outer ends of the 55 cross-bar 3 and are connected, substantially midway of their upper and lower ends by a cross-bar 8, while the rear corner bars 6, 6 are pivoted to the respective bars 1 and 2 in advance of the cross-bar 4, as at 9, and 60 are connected intermediate their ends by a cross-bar 10.

An upper frame is collapsingly carried by the corner uprights or bars 5 and 6 of the lower frame, and comprises the front corner 65 uprights or bars 11, 11 and the rear corner uprights or bars 12, 12, which pivotally rise from the upper ends of the respective uprights 5 and 6. The pivots 13, which connect the respective front uprights 5 and 11, 70 are disposed above the lower ends of the uprights 11 to provide such uprights with the downward extensions 14, which lap the sides of the lower uprights 5 and have their free ends notched to coact with pins 15 on the 75 respective bars 5 to permit the bars 5 and 11 to have folding or collapsing movements in a rearward but not in a forward direction from upright or vertical position. A cross-bar 16 forms the connecting pivot for each 80 pair of rear uprights 6, 12. A seat frame 17 has side-bars 18 which are pivotally connected at their front and rear ends to the respective front and rear bars 11, 12, such seat being disposed intermediate the lower 85 and upper ends of the bars 11, 12. Arm rests 19 are disposed in parallel relation to the seat 17 and are pivotally connected at their rear ends to the respective uprights 12 below the upper ends thereof, and are 90 pivotally connected at their forward ends to the upper ends of the respective uprights 11, as shown. A back 20 extends downward from the upper portion of the rear uprights 12, being pivotally connected at its lower 95 end to the seat bars 18 by links 21 and at its upper end to the upper end portions of the rear uprights 12, as at 22. The rear uprights 12, 12 are connected at their upper ends by a cross-bar or member 23, which is 100 preferably integral therewith.

24 designates a tray, which is carried by arms 25 that are pivoted at their rear ends to the respective rear uprights 12, as at 22, thus enabling the tray to rest in usable position on the arm rests 19 or to be swung back of the uprights 12, as shown in Figs. 2 and 3.

A foot-rest 26 is provided below the seat 17 and is carried, in the present instance, at the forward ends of horizontally-disposed side bars 27-27 in advance of the uprights 5 11, said side bars being pivotally carried at their rear ends by the cross-bars 16 and adjacent to their forward ends by the pivots 13.

A diagonally-disposed bracing link 28 is 10 disposed at each side of the chair and has its forward end pivotally carried by the seat pivot 29 of the respective front upright 11, and has its rear end pivotally connected to the rear upright 6 below the cross-bar 16, as at 30, thus causing the lower and upper frames of the chair to have uniform folding and unfolding movements, and preventing an independent folding or unfolding of one relative to the other.

20 A jointed brace 31, having a knee-joint 32, is disposed at each side of the lower frame of the chair and has its forward end pivotally connected to the respective end of the cross-bar 8 and its rear end pivotally connected by the pivot 9 to the respective frame upright 6. When the chair is in upright position the brace-bars 31 are in straight bracing relation and prevent a collapsing of the chair until the knee-joint 32 of each 30 bar is broken for such purpose.

33, 33 designate small wheels, which are carried by the cross-bar 4 near the ends thereof and are so disposed that they are free from contact with the floor or other 35 subjacent support when the feet 7 of the lower chair frame are resting on the floor. A slight rearward tilting of the chair will, however, move the wheels 33 into rolling contact with the floor. It frequently happens that a baby, when sitting in a high-chair, will push its feet against a table or other stationary means adjacent to which the chair is placed and cause a rearward tilting of the chair, which tipping sometimes 40 results in injury to the baby. By the provision of the wheel 33 it is impossible to tip the chair over in this manner, for as soon as it is tipped slightly to the rear, the wheels 33 will be brought into rolling contact with the floor so that the chair will roll outward in upright position from the object against which the baby is pushing.

It is preferable to make the frame parts of strap metal, as shown, as a chair of light 55 and strong construction is thereby provided. It is evident with this construction of chair that it is composed of few parts, and it is foldable into compact form for shipping or storing, as shown in Fig. 3, or may be 60 quickly and easily unfolded to set-up position, thus admirably adapting it for use by hotels, restaurants, and the like, as well as in private houses.

I wish it understood that my invention is

not limited to any specific construction, form 65 or arrangement of the parts, as numerous modifications may be made without departing from the spirit of the invention.

Having thus described my invention, what I claim as new, and desire to secure by Letters Patent, is,

1. A high chair comprising a base frame, a foot rest frame, a seat frame and a back, and means carrying said frames and back and operable to place said frames in parallel vertically spaced usable position with the back extending up at an angle from the said frame, or to place said frames and back in closely disposed substantially parallel collapsible position with the foot rest frame 80 and seat frame disposed between the base frame and back.

2. A high chair comprising a base frame, uprights supporting said base frame and projecting upward from the corners thereof, 85 a foot rest frame pivotally carried at the upper ends of said uprights, an upper set of uprights pivotally rising from said lower uprights with their pivots common to the foot rest frame pivots, a seat frame carried 90 by said upper set of uprights, and means for retaining said uprights in set-up position or operable to permit a collapsing of the uprights to place the base frame, foot rest frame and seat frame in closely disposed collapsible position.

3. A high chair comprising a base frame, corner uprights rising from said base frame and being pivotally jointed intermediate their ends to form upper and lower sections 100 which are collapsible one over the other, a foot rest carried by said sections at the point of jointure thereof, a seat pivotally carried by the upper section, arm rests pivotally carried by the upper section, means for 105 retaining said sections in set up position or operable to permit a collapsing thereof, to place the base frame, foot rest, seat and arms in closely disposed collapsed position, and means connecting said upright sections 110 for causing a uniform collapsing thereof.

4. A high chair comprising a base frame, uprights pivoted to said base frame and serving as supports therefor when in an upright position, a second set of uprights pivoted to the upper ends of the lower uprights with a portion of said upper set of uprights extended below their pivots and cooperating with the respective lower uprights to limit the setting up movements of the uprights, a 115 foot rest frame pivotally carried by said uprights with its pivots common to the pivots connecting the upper and lower sets of uprights, a seat frame and arm rests pivotally carried by the upper set of uprights, a back 120 frame pivotally rising from the seat and carried by the upper set of uprights, means for retaining the uprights in set up position,

and means connecting the upper and lower sets of uprights and operable to permit a uniform collapsing thereof whereby to place the base frame, foot rest frame, seat frame, 5 arm rests and back frame in substantially parallel closely disposed collapsed position.

In testimony whereof, I have hereunto

signed my name to this specification in the presence of two subscribing witnesses.

GEORGE H. BARSCHOW.
